LADY'S OVERTSHOE

Isabelle K. Tokarczyk, Forestville, Conn., assignor to United States Rubber Company, New York,
N. Y., a corporation of New Jersey

Application January 23, 1953, Serial No. 23,264

Term of patent 3½ years

(Cl. D7—4)

To all whom it may concern:

Be it known that I, Isabelle K. Tokarczyk, a citizen of the United States, residing at Forestville, in the county of Hartford and State of Connecticut, have invented a new, original, and ornamental Design for a Lady's Overshoe, of which the following is a specification, reference being had to the accompanying drawing, forming a part thereof.

Fig. 1 is a perspective view of a lady's overshoe, showing my new design;

Fig. 2 is a top view of same; and

Fig. 3 is a side view of same illustrating the opposite side from that shown in Fig. 1.

I claim:

The ornamental design for a lady's overshoe, substantially as shown.

ISABELLE K. TOKARCZYK.
